UNITED STATES PATENT OFFICE.

CULVER B. KNOX, OF GLEN RIDGE, NEW JERSEY, ASSIGNOR TO THE WHITEHEAD & HOAG COMPANY, OF NEWARK, NEW JERSEY, A CORPORATION OF NEW JERSEY.

SALT-SPOUT.

1,383,640.

Specification of Letters Patent.

Patented July 5, 1921.

Application filed October 8, 1920. Serial No. 415,695.

To all whom it may concern:

Be it known that I, CULVER B. KNOX, of Glen Ridge, in the county of Essex, in the State of New Jersey, have invented new and

5 useful Improvements in Salt-Spouts, of which the following, taken in connection with the accompanying drawings, is a full, clear, and exact description.

This invention relates to certain improvements in pouring spouts for receptacles used to hold powdered material such as sugar, salt, or any substance capable of being discharged through a relatively small opening.

The object of the invention is the production of a spout of relatively simple and inexpensive construction that will effectively perform the desired functions of such a device, and which by reason of its inherent resiliency normally assumes a substantially 20 flat or plane form, thereby closing the opening through the wall of the container without materially obstructing the interior of the container, the edged portions, or wings of the device constituting flexible means for holding the spout in its closed position.

Other objects and advantages relate to the details of form and construction of the device, as will more fully appear from the following description, taken in connection with 30 the accompanying drawings, in which:

Figure 1 is a top plan view of the spout applied to the cover of a receptacle.

Fig. 2 is a bottom plan view of the same.

Fig. 3 is a cross section on line 3—3, Fig. 1.

Fig. 4 is a view similar to Fig. 1, illustrating the spout in its open or pouring position.

Fig. 5 is a cross section on line 5—5, Fig. 4.

40 The spout, as illustrated, consists of a substantially flat sheet of material cut in the form shown, and may be constructed of any suitable flexible resilient material such as celluloid, or products of a similar nature, or 45 other material having the desired flexibility and resiliency.

Although the device is so formed of a single sheet for the purpose of identification, it may be said that the device comprises a central top portion 1—1 in the form of the vertical section of a frustum of a cone, and opposite substantially sector-shaped wings 2—2 and 3—3, the central portion having its opposite ends provided with projecting tongues 4—4 and 5—5 respec-

tively, and the wings 2—2 and 3—3 having at their outer edges substantially radially projecting lugs, or stops, 6—6 and 7—7 respectively.

The device so shaped is adapted for co-operation with the wall of the receptacle formed with an opening similar in shape to the central or top portion 1—1 of the spout. The walls of this opening are formed along straight lines, the opening being narrower 60 at the end with which the tongue 5—5 is adapted to engage, such tongue resting upon the outer surface of the wall of the receptacle at one end of the opening, and the tongue 4—4 resting upon the outer surface of the 65 wall of the receptacle at the other end of the opening.

The device is readily insertible in the opening in the receptacle at any time by merely bending it to the desired spout shape 70 form, then inserting the lugs 6—6 and 7—7 beneath the wall 8—8 of the receptacle, and then pushing the spout downwardly, when by reason of its resiliency and its natural tendency to assume a flat position, the device 75 automatically springs to closed position.

The wings 2—2 and 3—3 should be of sufficient width at their rear portions 9—9 and 10—10 to resiliently grip the adjacent tapered side walls of the opening when the 85 spout is moved about the flap 5—5 as a pivot to thereby frictionally hold that end of the spout in position at the opening.

By merely gripping the tongue 4—4, the spout is readily flexed and moved to open 90 pouring position until the lugs 6—6 and 7—7 engage the wall 8—8 of the container. In such position the spout is of substantially arched form in cross-section, and tapers toward the end which carries the 95 tongue 5—5.

In closed position of the spout, the wings 2—2 and 3—3 lie in substantial contact with the interior surface of the container so as not to obstruct the space within the container and so that the weight of the contained material pressing these wings against the wall of the container normally assists the resiliency of the device in maintaining the device in position to close the opening 105 through the container wall.

The construction and operation of the device will be readily understood from the drawings, and the foregoing description, and although I have shown and described a 110

specific form of device, including preferred details, I do not desire to limit myself to the exact form and construction of the device as various changes and modifications may be 5 made without departing from the invention as set forth in the appended claims:

1. The combination with a container wall having an opening therethrough, of a pouring spout located in said opening, and comprising 10 a substantially flat sheet of flexible material capable of being flexed to substantially U-shaped form and of returning by its own resiliency to substantially flat form after each flexing operation.
- 15 2. The combination with a receptacle having an opening through a wall thereof of a pouring spout, comprising a substantially flat sheet of flexible material, capable of being flexed in substantially U-shaped form, 20 and of returning by its own resiliency to substantially flat form after each flexing operation, said sheet having tongues projecting in opposite directions therefrom and adapted to engage the exterior of said cover.
- 25 3. The combination with a receptacle having an opening through a wall thereof, of a pouring spout, comprising a substantially flat sheet of flexible material, capable of being flexed in substantially U-shaped form, 30 and of returning by its own resiliency to substantially flat form after each flexing operation, said sheet having tongues projecting in opposite directions therefrom and adapted to engage the exterior of said cover, 35 and additional flanges projecting therefrom adapted to engage the interior of the cover when the spout is flexed and moved to pouring position.
4. The combination with a container 40 formed with a dispensing opening of a substantially flat sheet of flexible material having a central portion adapted to substantially close said opening, and wing portions positioned within the receptacle, said sheet 45 being capable of being flexed by the walls of said opening to substantially U-shaped form

when drawn therethrough by tension applied upon the front edge of the central portion of said sheet, and of returning by its own resiliency to substantially flat form 50 after each flexing operation.

5. The combination with a container formed with a dispensing opening of a substantially flat sheet of flexible material having a central portion adapted to substantially close said opening, and wing portions positioned within the receptacle, said sheet being capable of being flexed by the walls of 55 said opening to substantially U-shaped form when drawn therethrough by tension applied upon the front edge of the central portion of said sheet, and of returning by its own resiliency to substantially flat form 60 after each flexing operation, and lugs formed on said sheet and adapted to contact with the inner surface of said receptacle to limit the outward flexing movement of said sheet.

6. The combination with a container formed with a dispensing opening, of a substantially flat sheet of celluloid having a 70 central portion adapted to close said opening, and wing portions positioned within the receptacle, and a flange projecting from said central portion and adapted to contact with the outer surface of said receptacle, said 75 sheet capable of being flexed by the walls of said opening to substantially U-shaped form when drawn therethrough by tension applied to the sheet, and of returning by its own resiliency to substantially flat form 80 after each flexing operation, and lugs formed in connection with said sheet adapted to contact with the interior surface of said receptacle to limit the outward flexing movement of said sheet.

In witness whereof I have hereunto set my hand this 4th day of October 1920.

CULVER B. KNOX.
